COMBINED BEVERAGE SERVER, COVER AND BASE THEREFOR

Bjorn Wiinblad, Hjortekaer, Denmark, assignor to Rosenthal-Porzellan Aktiengesellschaft, Selb, Bavaria, Germany, a corporation of Germany

Continuation of design applications Ser. No. 82,308 and Ser. No. 82,326, Oct. 26, 1964. This application July 16, 1965, Ser. No. 86,488

Claims priority, application Germany Apr. 25, 1964

Term of patent 14 years

(Cl. D44—26)

FIG. 3.

FIG. 4.

FIG. 7.

FIG. 8.

FIGURE 1 is a side elevational view of a combined beverage server, cover and base therefor showing my new design as embodied in a server having the size and proportions of a coffee pot;

This is a continuation of my earlier filed applications D.82,308 and D.82,326 of October 26, 1964, both now abandoned.

I claim:

The ornamental design for a combined beverage server, cover and base therefor, as shown and described.
